FIG. 7

To all whom it may concern:

Be it known that we, Walter Dorwin Teague and Charles A. Jerabek, citizens of the United States, residing, respectively, at Annandale, Hunterdon County, State of New Jersey, and at Bay Shore, Suffolk County, State of New York, have invented a new, original, and ornamental Design for a Grand Piano, of which the following is a specification, reference being had to the accompanying drawings, forming a part hereof, wherein:

Fig. 1 is a perspective view of a grand piano, showing our new design;

Fig. 2 is a front elevational view thereof;

Fig. 3 is a side elevational view thereof, a portion of the case being broken away for purposes of illustration;

Fig. 4 is a top plan view thereof;

Fig. 5 is a fragmentary bottom plan view of the rear and rear leg portions thereof;

Fig. 6 is a side elevational view of that shown in Fig. 5 with the case portion being omitted for convenience of illustration; and,

Fig. 7 is a fragmentary side elevational view taken from line 7—7 of Fig. 6.

We claim:

The ornamental design for a grand piano, as shown.
